(57) **CLAIM**

The ornamental design for a foldable structure for one or more antennas, as shown and described.

DESCRIPTION

FIG. 1 is a top-left isometric view of a foldable structure for one or more antennas showing the new design, where a movable part of the foldable structure for one or more antennas is in an upright position.

FIG. 2 is a front view thereof, where the movable part of the foldable structure for one or more antennas is in the upright position.

FIG. 3 is a rear view thereof, where the movable part of the foldable structure for one or more antennas is in the upright position.

FIG. 4 is a right side view thereof, where the movable part of the foldable structure for one or more antennas is in the upright position.

FIG. 5 is a left side view thereof, where the movable part of the foldable structure for one or more antennas is in the upright position.

FIG. 6 is a top view thereof, where the movable part of the foldable structure for one or more antennas is in the upright position.

FIG. 7 is a bottom view thereof, where the movable part of the foldable structure for one or more antennas is in the upright position.

FIG. 8 is a top-left isometric view thereof, where the movable part of the foldable structure for one or more antennas is in a folded or collapsed position.

FIG. 9 is a front view thereof, where the movable part of the foldable structure for one or more antennas is in the folded or collapsed position.

FIG. 10 is a rear view thereof, where the movable part of the foldable structure for one or more antennas is in the folded or collapsed position.

FIG. 11 is a right side view thereof, where the movable part of the foldable structure for one or more antennas is in the folded or collapsed position.

FIG. 12 is a left side view thereof, where the movable part of the foldable structure for one or more antennas is in the folded or collapsed position.

(Continued)

FIG. 13 is a top view thereof, where the movable part of the foldable structure for one or more antennas is in the folded or collapsed position; and,

FIG. 14 is a bottom view thereof, where the movable part of the foldable structure for one or more antennas is in the folded or collapsed position.

The broken lines in the drawings illustrate portions of the foldable structure for one or more antennas which form no part of the claimed design.
